RHEOSTAT

Earl F. Mekelburg, Wauwatosa, Wis., assignor to Square D Company, Detroit, Mich., a corporation of Michigan

Application July 5, 1952, Serial No. 297,347

7 Claims. (Cl. 201—62)

This invention relates in general to rheostates; more particularly this invention relates to a rheostat of novel construction which may employ a plurality of types of current limiting elements.

One object of the present invention is to provide an improved rheostat which is economical to construct and maintain.

Another object of the present invention is the provision of a rheostat of new and improved form in which the current limiting elements may be readily changed.

Another object of the present invention is the provision of a new and improved rheostat having a plurality of paths therethrough for the passage of current.

Another object is the provision of a novel rheostat in which the amount of movement required of the element effecting the insertion of varying amounts of resistance in the electrical circuit is minimized.

Another object of the present invention is the provision of a rheostat having a rectilinearly operating control member which carries no current.

Another object is the provision of an improved rheostat in accordance with the preceding object in which lateral force on the operating member is substantially minimized.

Another object of the present invention is the provision of a new and improved rheostat having a rectilinearly operable control member for varying the effective resistance of the device, the new rheostat employing no flexible leads or "pig tails" whatsoever.

Another object of the present invention is the provision of a new and improved rheostat which may employ ribbon resistors, wire wound resistors, or similar current limiting elements with equal facility.

Other objects and features of the invention will be readily apparent to those skilled in the art from the specification and appended drawing illustrating certain preferred embodiments in which:

Figure 1 is a front elevational view of the device of the present invention.

Figure 2 is an enlarged sectional view on the plane of line II—II of Figure 1.

Figure 3 is a partial sectional view along the plane of line III—III of Figure 2.

The device of the present invention comprises an enclosing case 1 comprising a base 2 having outer brackets 3 mounted thereto, as by welding, the brackets 3 serving to mount a cover 4. Screws 5 are provided which maintain the cover 4 in position as illustrated in Figure 2. To the inner surface of base 2 there are mounted a plurality of insulating plates 6 by means of bolts 7 and 8. Nuts 9 and 11 cooperate with bolts 7 and 8, respectively, to maintain plates 6 in position.

Spaced from the bolt 7 is a bolt 12, also projecting through the rear surface of the base 2, the bolt 12 being of conducting material and having its inner end mechanically and electrically connected to a conducting plate 13 by peening, welding or other suitable method. Extending through a suitable aperture in plate 13 is an elongated

2

bolt 14, upon which there is mounted a plurality of conducting segments 15, 16, 17, 18, 19, 21 and 22, these segments being separated from the bolt 14 by a suitable insulating sleeve 23.

As may be seen from an inspection of Figure 2, the segment 15 adjacent to plate 13 is electrically connected thereto, the opposite side of segment 15 being electrically connected to one end of a ribbon resistor 25, an insulating piece 24 being interposed between this end of the ribbon resistor 25 and segment 16. The opposite end of resistor 25 engages the opposite face of segment 16 so as to be electrically connected thereto, and is further electrically connected to one end of the adjacent ribbon resistor 26 which is insulated from the adjacent side of segment 17 by an insulating piece 27. As illustrated in Figure 2, other ribbon resistors 28 and 29, and a wire wound resistor 31, are provided and are assembled together with other insulating pieces 32, 33 and 34, and segments 18, 19, 21 and 22 in substantially the same manner as has previously been described for the assembly of the resistors 25 and 26. No insulating piece is interposed between segments 21 and 22. As will be seen from Figure 2, resistors 25, 26, 28, 29 and 31 and the insulating pieces 24, 27, 32, 33 and 34 are all positioned upon the bolt 14, the wire wound resistor being mounted thereto by end pieces 30.

Adjacent to, but spaced from, the bolt 8 is a conducting bolt 35 which extends through base 2 and is electrically and mechanically connected to the conducting plate 36 which is disposed at its interior end. A bolt 37 extends through base 2 and a suitable hole in the plate 36 and supports, in the manner described in the paragraph immediately preceding, a plurality of resistance elements 38, 39, 41 and 42 which are of the ribbon type, and a single resistance element 43 of the wire wound type. In addition, there are mounted upon the bolt 37 conducting segments 50 through 56 comparable to and mounted as are the segments 15 through 19, 21 and 22 aforementioned. Insulating pieces 45 through 49 are provided and are interposed between the conducting segments 50 through 56 in the manner illustrated. An insulating sleeve 44 is provided which is similar to the insulating sleeve 23 aforementioned. For a reason to be substantially explained, the segments 50 and 15 are made of different size, while all of the other segments are of the same size, whereby the junctures between the segments of one "stack" are not aligned with junctures between the segments of the other "stack."

An insulating plate 57 joins the ends of the bolts 14 and 37 and nuts 58 and 59 are disposed upon the ends of bolts 14 and 37 respectively. It will be obvious that all of the resistor elements may be of the ribbon type if desired, or all of the resistance elements may be of the wire wound type. It will further be obvious that any combination of these and other similar types of current limiting elements may be utilized, and that the number of segments and current limiting elements employed may be varied.

Interposed between the bolts 14 and 37 and the stacks of segments which each carries is an operating shaft 61 which projects through suitable apertures in the base 2 and the cover 4. Riveted to the operating shaft 61 are a pair of laterally extending arms 62. Each of the arms 62 has an opening at each end in which there are disposed a spring 63 and a conducting brush 64, an insulating bar 65 being interposed between the biasing spring 63 and the brush 64. As will be seen from Figure 3, the spring 63 forces the brushes 64 into tight engagement with the conducting segments. The arms 62 are provided with projecting portions 66 which fit into the longitudinally extending openings in the springs 63 to maintain them in position. Springs 63 apply substantially equal and op-

posed forces, the resulting lateral force on shaft 61 being thereby minimized.

In the operation of the device, the bolts 12 and 35 are connected in the electrical circuit in which the amount of current is to be controlled. Assuming that the bolt 12 is connected to the more positive potential, current will flow through the bolt 12 and plate 13 into segment 15. With the operating shaft 61 in the position illustrated in Figure 2, current will then flow through resistors 25, 26, 28, 29 and 31, and through the segments 21 and 22 into both brushes 64. Current will then flow through these brushes into the segments 55 and 56 and through the resistors 43, 42, 41, 39 and 38 into segment 59, plate 36 and out of the device through bolt 35.

If operating shaft 61 were moved toward the left, from the position of Figure 2, so that the brushes 64 were carried thereby toward the left, circuit current will flow through fewer resistance elements. Furthermore, it will be seen that due to the relative lateral displacement between the junctures of conducting segments in one row and the junctures of the conducting segments in the other row, adequate area of contact between the brushes and the segments is always maintained whereby current carrying ability is not impaired. It will further be seen that when operating shaft 61 is moved into its most left position, from the view of Figure 2, no resistance is in the electrical circuit of this device, and that this "no resistance" position is attained without an opening of the circuit whereby burning of brushes and segments when controlling inductive loads is eliminated.

It will readily be apparent that the device of the present invention is readily fabricated and that the contacting surfaces may be sanded or faced with ease. The conducting segments may be of any suitable size, and may be inexpensive stampings. Furthermore, it is readily apparent that various types of current limiting elements may be employed, and that the device utilizes a movable operating lever positionable at will to smoothly vary the amount of resistance in the electrical circuit to the device, but no flexible leads, "pig tails," or the like, need be employed. The operating lever of the present invention carries no current whatsoever and is isolated from the electrical circuits, while other elements of the device present a plurality of paths for current flow through the structure.

While certain preferred embodiments of the invention have been specifically disclosed, it is understood that the invention is not limited thereto, as many variations will be readily apparent to those skilled in the art and the invention is to be given its broadest possible interpretation within the terms of the following claims.

What is claimed is:

1. In a device for regulating current flow having a pair of terminals for connection to an electrical circuit, a plurality of conducting segments, a pair of spaced bolts supporting said segments in a pair of spaced rows, insulating means disposed upon said bolts between certain of said segments, other insulating means disposed between said bolts and said segments, first impedance means electrically interconnecting the segments of one of said rows, the ends of said first impedance means being mounted on one of said bolts, second impedance means electrically interconnecting the segments of the other of said rows, the ends of said second impedance means being mounted on the other of said bolts, one of said rows being electrically connected to one terminal while the other of said rows is electrically connected to the other of said terminals, a pair of movable conducting means, means mounting one of said movable means in engagement with one side of both of said rows of segments, means mounting the other of said movable means in engagement with the opposite side of both of said rows of segments, and means for moving said movable means along said rows to effect the insertion of variable portions of said impedance means in the electrical circuit between said terminals.

2. In a device for regulating current flow having a pair of terminals for connection to an electrical circuit, a plurality of conducting segments, means supporting said segments in two rows, insulating means separating said segments, first impedance means electrically interconnecting the segments of one of said rows, second impedance means electrically interconnecting the segments of the other of said rows, one of said rows being electrically connected to one terminal while the other of said rows is electrically connected to the other of said terminals, a pair of movable conducting means, an operating lever for rectilinearly moving said movable means, means mounting one of said movable means in engagement with one side of both of said rows and mounting the other of said movable means in engagement with the opposite side of both of said rows, said last mentioned means including one spring biasing said one movable means toward said rows and a second spring biasing said other movable means toward said rows, said springs applying substantially equal and opposite forces whereby the resultant lateral force on said operating lever is minimized, said movable means being positionable by said operating lever along said rows to effect the insertion of variable portions of said impedance means in the electrical circuit between said terminals.
3. In a device for regulating current flow having a pair of terminals for connection to an electrical circuit, a plurality of conducting segments, a pair of spaced bolts supporting said segments in a pair of spaced rows, insulating means disposed upon said bolts between certain of said segments, other insulating means disposed between said bolts and said segments, first impedance means electrically interconnecting the segments of one of said rows, the ends of said first impedance means being mounted on one of said bolts, second impedance means electrically interconnecting the segments of the other of said rows, the ends of said second impedance means being mounted on the other of said bolts, a pair of movable conducting means for bridging said rows, an operating lever for rectilinearly moving said movable means, means mounting one of said movable means in engagement with one side of both of said rows and mounting the other of said movable means in engagement with the opposite side of both of said rows, said last mentioned means including springs biasing said movable means toward said rows, said springs applying substantially equal and opposite forces whereby the resultant lateral force on said operating lever is minimized, said movable means being positionable by said operating lever along said rows to effect the insertion of variable portions of said impedance means in the electrical circuit between said terminals.
4. In a device for regulating current flow having a pair of terminals for connection to an electrical circuit, a first bolt, a first stack of elements assembled thereon including a plurality of first conducting segments mounted upon said first bolt, means insulating said first segments from said first bolt, a plurality of first insulating pieces mounted upon said first bolt, a plurality of first resistors of substantially U shape mounted upon said first bolt, said device being so constructed and arranged that both ends of said first resistors are mounted upon said first bolt and disposed between the ends of each first resistor are at least one of said first segments and at least one of said first insulating pieces whereby no electrical circuit between adjacent first segments exists except through said first resistors, removable means for tightly maintaining said first segments, first insulating pieces and first resistors in position upon said first bolt, means electrically connecting said first stack of elements to one of said terminals; a second bolt spaced from said first bolt, a second stack of elements assembled upon said second bolt including a plurality of second conducting segments mounted upon said second bolt, means insulating said second segments from said second bolt, a plurality of second insulating pieces mounted upon said second bolt, a plurality of

second resistors of substantially U shape mounted upon said second bolt, said device being so constructed and arranged that both ends of said second resistors are mounted upon said second bolt and disposed between the ends of each second resistors are at least one of said second segments and at least one of said second insulating pieces whereby no electrical circuit between adjacent second segments exists except through said second resistors; removable means for tightly maintaining said second segments, second insulating pieces and second resistors in position upon said second bolt; means electrically connecting said second stack of elements to the other of said terminals; a pair of movable conducting means, means mounting one of said pair of movable conducting means in engagement with one side of both of said stacks and mounting the other of said pair of movable conducting means in engagement with the opposite side of both of said stacks, and a rectilinearly movable operating lever connected to said last mentioned means and movable to adjustably position said movable conducting means to effect the insertion of variable portions of said resistors in the electrical circuit between said terminals.

10
15

5. The device defined in claim 4 in which said means mounting said movable conducting means includes an insulating bracket which positions both of said movable conducting means in substantially the same plane.

6. The device defined in claim 4 in which said means mounting said movable conducting means includes an insulating bracket which positions both of said movable conducting means in substantially the same plane, and which also includes a spring associated with each of said movable conducting means acting to bias said movable conducting means toward said stacks.

7. The device defined in claim 6 in which said springs are so constructed and arranged that they apply substantially equal and opposed biasing forces whereby the resulting lateral thrust on said operating lever is minimized.
